UNITED STATES PATENT OFFICE.

PETER A. DEASY, OF OAKLAND, CALIFORNIA, ASSIGNOR TO DEASY UTILITIES COMPANY, OF OAKLAND, CALIFORNIA, A CORPORATION.

DESIGN FOR A WATER-HEATER.

46,048.

Specification for Design.

Patented July 7, 1914.

Application filed May 9, 1913. Serial No. 766,610. Term of patent 3½ years.

To all whom it may concern:

Be it known that I, PETER A. DEASY, a citizen of the United States, residing at Oakland, in the county of Alameda and State of California, have invented a new, original, and ornamental Design for Water-Heaters, of which the following is a specification.

The drawing represents a side elevation of my water heater.

I claim:

The ornamental design for a water heater, as shown.

In testimony whereof I affix my signature in presence of two witnesses.

PETER A. DEASY.

Witnesses:

F. P. SCHROEDER,
FRANK H. CARTER.
